PROTECTIVE COVERING FOR ICE REMOVAL
FROM AIRFOILSAlbert M. La Rue, Akron, Ohio, assignor to The
B. F. Goodrich Company, New York, N. Y., a
corporation of New York

Application February 27, 1947, Serial No. 731,179

12 Claims. (Cl. 244—134)

1

The invention relates to protective coverings suitable for ice-removal and especially to inflatable coverings for airfoils and the surfaces of other structures exposed to flow of air under icing conditions.

Prior inflatable coverings have generally utilized cyclical inflation of tubes in alternation for removing the ice from airfoils; but under some icing conditions have not been fully effective in breaking the bond of the ice. The prior coverings have depended largely upon the distension at the tube areas for cracking and loosening the ice deposited thereon resulting sometimes in pieces of ice of substantial extent remaining adhered to the coverings despite the inflation and distension actions. The construction of such inflatable coverings has also been found to be relatively expensive and time-consuming and for some applications relatively heavy.

An object of the invention is to overcome the foregoing and other difficulties and disadvantages of prior inflatable coverings.

Other objects are to provide an improved protective covering; to provide for distortion of the covering and for assisting the ice-removing action by compelling shifting movement of the outer surface thereof; to provide for restraining outward distension and separating movement of the outer wall of the covering coincidentally with effecting a shifting and/or rolling action of the same in the direction across the direction of separating movement; to provide for effecting the outward distension and the shifting action at a plurality of adjacent regions of the covering; and to provide for simplicity of construction, convenience of manufacture and for light weight and effectiveness of operation.

These and other objects and advantages of the invention will be apparent from the following description.

In the accompanying drawings, which form a part of this specification and in which like numerals are employed to designate like parts throughout the same;

Fig. 1 is a perspective view from above of an apparatus or protective covering mounted on the leading edge of an aircraft wing and constructed in accordance with and embodying the invention, parts being broken away and in section;

Fig. 2 is a plan view of the covering before its attachment to the wing, parts being broken away;

Fig. 3 is a sectional view taken along line 3—3 of Fig. 2, parts being broken away;

Fig. 4 is a diagrammatic view of a section of

2

the covering like Fig. 3 and having broken lines showing the position of parts under inflation of the covering.

Fig. 5 is a perspective view from an end of the covering showing the latter in the inflated condition, parts being broken away and in section;

Fig. 6 is a view like Fig. 2 but showing a modified construction of the covering, parts being broken away, and

Fig. 7 is a sectional view taken along line 7—7 of Fig. 6.

In the illustrative form of the invention shown in Figs. 1 to 5, the construction of an apparatus or inflatable covering 10 of resilient rubber or other rubber-like material includes restraining means 18 arranged in the covering in a manner to compel shifting movement of the outer surface of the covering in a chordwise direction under an outward distending movement of the outer surface. The construction thus provides rolling, shearing and distorting actions throughout the entire distensible area of the covering to remove the overlying ice-deposit. The covering 10 is mounted on the leading edge of an airfoil or aircraft wing 12, being disposed, for example, at the outboard side of an engine nacelle 13 or other component of the aircraft. The covering may be attached to the airfoil in any suitable manner, such as by rubber cement 11 or other suitable adhesive.

The covering 10 has an inner wall 14 of suitable rubber-like material desirably reinforced as by non-stretchable sheet material such, for example, as square-woven textile fabric 15 of cotton, glass fibers, silk, or other suitable natural or synthetic filamentary material. The inner wall 14 being in adhered relation to the surface of the wing, is thus supported uniformly by the latter.

The covering 10 also has an outer wall 16 of distortable material, preferably resilient rubber-like material, in separated relation with respect to the inner wall 14 for facilitating the outward distension or distortion and separating movement of the outer wall under inflation of the covering. The outer wall 16 may be reinforced with a highly stretchable fabric sheet material 17 such, for example, as elastic fabric or stockinet fabric of suitable filamentary material. The stretchable reinforcement assures continuity of transmittal of the separating and the shifting movements uniformly throughout the rubber material of the outer wall.

To the ends of restraining the separating move-

ment of the outer wall and compelling lateral or chordwise shifting movement thereof, the invention provides the means 18 comprising a plurality of interposed restraining elements 18, 18 of flexible material connecting the inner and outer walls in an offset manner unidirectionally of the covering, as shown in the drawings. Preferably, the elements 18, 18 are in the form of partition elements of flexible strip material such, for example, as woven textile fabric, which fabric may be stretchable or non-stretchable, as desired, and may be made impervious, if desired, as by a coating or impregnation of suitable rubber-like material for providing a plurality of inflatable passages in the covering adapted to be inflated simultaneously or independently, as desired.

The partition elements 18, 18 are disposed between the inner and outer walls 14, 16, and are spaced apart in chordwise series and extend spanwise in side-by-side, adjacent relation one to another along the covering throughout the extent of the distensible area thereof and substantially coextensive with the length thereof. However, some of the elements at the sides of the covering may be of lesser length to conform to the shape of the covering, as shown especially in Fig. 2.

For joining the partition elements 18, 18 to the inner and outer walls, each element may be cemented to the walls or otherwise secured thereto, and may be adhesively attached along side marginal portions 19, 20 of the element as by a suitable rubber cement, as shown especially in Fig. 5. The partition elements are joined to the outer wall along spanwise lines parallel one to another and at positions offset chordwise with relation to their positions of joinder with the inner wall in a manner to effect swinging movement of the partition elements in a chordwise direction under the distention of the outer wall and the separating movement thereof relative to the inner wall to compel shifting movement of the outer wall.

In the embodiment shown in Fig. 2, the shifting movement is all in one fore and aft or chordwise direction of the covering, although other arrangements of shifting movement may be provided, if desired. For example, the partition elements may be offset or shaped in a portion of the covering in a different and opposite manner from that in another portion of the covering so as to compel the shifting movement of the portions in different directions, such as toward each other or away from each other.

Under inflation of the covering and the separating movement of the outer wall, the partition elements 18, 18 move with the outer wall and swing about their spanwise lines of joinder to the inner wall from the position adjacent the inner wall, as shown especially in Fig. 3 and in full lines in Fig. 4, to substantially the position shown in broken lines in Fig. 4 and the position shown in Fig. 5. This swinging action of the partition elements 18, 18 compels shifting movement of the outer wall relative to the inner wall in the opposite chordwise direction to that of the direction of offset attachment, that is, in the direction across the direction of separating movement. The shifting movement occurs concurrently with the distention and rolling action of the outer wall under the inflation of the covering. In this manner, the overlying ice deposit is subjected to lateral or chordwise shearing action by the shifting movement of the outer wall for breaking effectively the adhesive bond at the interface between the ice and the outer wall, and in addition the ice deposit is subjected to outward dis-

ortion for breaking the ice into pieces and further reducing the adhesive bond of the latter.

For inflating the covering, a flexible conduit or hose 21 is attached to the inner wall 14 in communication with the space between the inner and outer walls, which conduit 21 may be connected to a suitable source of air under pressure in the structure of the aircraft. The partition elements 18, 18 may be provided with spaced apertures 22, 22 in series along their length in register one to another chordwise of the covering for the purpose of simultaneous inflation of all the passages, as shown especially in Fig. 5. The construction provides for intercommunication of the inflatable passages one to another through the walls thereof, that is the partition elements, facilitating the separating movement and shifting movement of the outer wall 16 simultaneously throughout the extent of the covering under inflation for effecting complete and prompt removal of the ice-deposit.

The covering may be rectangular or tapered or otherwise suitably shaped in form to conform to the shape of the wing and to provide the desired extent of chord-coverage of the wing. The partition elements adjacent the spanwise attaching margins 23, 24 may be of shorter length than the partition elements inwardly of the first said partition elements, when the covering is tapered in form. The fabric and rubber parts of the covering 10 are united integrally and, desirably by vulcanization under heat and pressure. The construction described hereinabove provides for light weight and strength for the purpose in combination with thinness and flexibility and smoothness of the covering facilitating convenience of attachment and smooth conformance of the covering to the surface of the leading edge, which conformance is advantageous for maintaining the aerodynamic characteristics of the wing.

In the operation of the covering 10 thus mounted on the leading edge of the wing, the admittance of air under pressure through the conduit 21 to the space between the inner and outer walls of the covering inflates the latter simultaneously throughout the distensible area occupied by the partition elements 18, 18. Since the inflatable passages provided by the plurality of the partition elements 18, 18 are in communication with one another, all of the passages are inflated simultaneously, resulting in the outward distention or bulging and separating movement of the entire outer wall at the distensible area. The separating movement of the outer wall causes the entire chordwise series of interposed partition elements to swing about their spanwise lines of joinder with the inner wall and thus limit the extent of the separating movement coincidentally with compelling shifting of the outer wall relative to the inner wall in the opposite chordwise direction of offset attachment of the partition elements to the inner and outer walls.

The inflation thus distends the outer wall 16 into a chordwise series of spanwise extending outward bulges which rapidly change contour during the inflation to assume a substantially ridge-like form having sharp radius of curvature, each bulge being formed intermediate the respective lines of joinder of the partition elements 18, 18 to the outer wall. The bulging or distending action of the outer wall taking place coincidentally with the swinging movement of the partition elements effects a rolling action of the outer wall at each bulge during the formation of the latter.

while the swinging action of the partition elements compels lateral or chordwise shifting movement of the outer wall effecting a shearing action on the adhesive bond at the interface between the ice and the covering at each minute area of the outer wall overlying the partition elements. The aforesaid outward distention and separating movement of the outer wall, in combination with the shifting movement thereof, thus effect breakage of the adhesive bond and in addition break the overlying ice deposit into pieces for prompt and thorough removal of the ice by the scavenging action of the flow of air across the wing.

The modified construction 25 of the covering, shown in Figs. 6 and 7, is substantially like that described hereinabove for the covering 10 except that the interposed partition elements 26, 27 have a different offset attaching arrangement and, unlike the partition elements 18, 18, do not extend continuously from end to end of the covering but are of relatively short spanwise extent. The outer wall 16 is arranged in a plurality of panels 28, 29 spaced apart spanwise and extending chordwise of the covering in parallel relation one to another, and a plurality of the interposed partition elements 26, 27 are disposed at each of the panels.

The partition elements 26, 27 are positioned spaced-apart in chordwise series and extend spanwise of the covering coextensive with the spanwise extent of each panel, as shown especially in Fig. 6, providing inflatable passages in communication with one another at the respective ends of each of the chordwise series of partition elements. Preferably, although not necessarily limited thereto, the partition elements 26, 27 are not apertured but present an unbroken wall throughout their spanwise extent.

The interposed partition elements 26, 27 are joined to the inner and outer walls 14, 16, respectively, in an offset attachment arrangement to effect the desired swinging action of the partition elements 26, 27. The partition elements 26, 27 are constructed and arranged at adjacent panels 28, 29 in a manner to compel the shifting of the outer wall 16 at such adjacent panels in opposed chordwise directions, as indicated by the arrows at 30 and 31. The arrangement is such that the chordwise offset attachment of the partition elements 26 is opposite that of the chordwise offset attachment of the partition elements 27, as shown especially in Fig. 7.

Under inflation of the covering 25, the outer wall 16 at the respective panels 28, 29 is bulged outwardly, as described hereinabove, for the covering 10, while the shifting movement at the adjacent panels 28, 29 occurs in opposed chordwise directions. This results advantageously in combining a twisting action at the outer wall with the desired outward distention and separating movement thereof and the shifting movement thereof in a chordwise direction, all of which effectively breaks the adhesive bond between the ice and the covering and breaks the ice into pieces for removal by the scavenging effect of the flow of air.

Variations may be made without departing from the scope of the invention as it is defined in the following claims.

I claim:

1. Apparatus for preventing the accumulation of ice upon a surface, said apparatus comprising a covering having an inner wall, an outer wall of distortable material in separated relation with

respect to said inner wall, means for effecting separating movement of said outer wall relative to said inner wall, and interposed restraining elements connecting said walls and joined to said outer wall at positions offset unidirectionally of the covering with relation to their positions of joinder with said inner wall in a manner to effect swinging movement of said elements under the separating movement of said outer wall to compel shifting of said outer wall relative to said inner wall unidirectionally of the covering in the direction opposite with respect to the direction of offset and across the direction of said separating movement.

15. 2. Apparatus for preventing the accumulation of ice upon a surface, said apparatus comprising a covering having an inner wall, an outer wall of elastic material in separated relation with respect to said inner wall, means for distending said outer wall and effecting separating movement thereof relative to said inner wall, and interposed restraining elements of flexible material connecting said walls and joined to said outer wall at positions offset unidirectionally of the covering with relation to their positions of joinder with said inner wall in a manner to effect swinging movement of said elements under the separating movement of said outer wall to compel shifting of said outer wall relative to said inner wall unidirectionally of the covering in the direction opposite with respect to the direction of offset and across the direction of said separating movement.

3. Apparatus for preventing the accumulation of ice upon a surface, said apparatus comprising an inflatable covering having an inner wall, an outer wall of resilient rubber-like material in separated relation with respect to said inner wall, means for inflating said covering to distend said outer wall and effect separating movement thereof away from said inner wall, and a plurality of interposed restraining elements of flexible material connecting said walls and joined to said outer wall at positions offset in the direction toward a margin of the covering with relation to their positions of joinder with said inner wall in a manner to effect swinging movement of said elements under the distention and separating movement of said outer wall to compel shifting of said outer wall relative to said inner wall in the direction opposite with respect to said direction toward said margin of the covering and across the direction of said separating movement.

4. Apparatus for preventing the accumulation of ice upon a surface, said apparatus comprising a covering having an inner wall, an outer wall of distortable material in separated relation with respect to said inner wall, means for distorting said outer wall and effecting separating movement thereof away from said inner wall, and interposed partition elements of strip material extending side-by-side in said covering in a direction thereof in spaced-apart relation one to another and connecting said walls and joined to said outer wall at positions offset in a direction across the first said direction with relation to their positions of joinder with said inner wall in a manner to effect swinging movement of said elements under said separating movement of said outer wall to compel shifting of said outer wall relative to said inner wall in the direction opposite with respect to the direction of offset and across the direction of said separating movement.

5. Apparatus for preventing the accumulation of ice upon the leading edge of an airfoil, said apparatus comprising an inflatable covering of resilient rubber-like material for said leading edge having an inner wall, an outer wall of said material in separated relation with respect to said inner wall, means for inflating said covering to distend said outer wall and effect separating movement thereof away from said inner wall, and a plurality of interposed partition elements of flexible strip material extending in side-by-side relation one to another along said covering and disposed spaced-apart in series across the covering providing a plurality of inflatable passages, said elements connecting said walls and being joined to said outer wall at positions offset in a direction across the covering with relation to their positions of joinder with said inner wall in a manner to effect swinging movement of said elements under inflation of said passages and said separating movement of said outer wall to compel shifting of said outer wall relative to said inner wall in the opposite direction with respect to the first said direction across the covering.

6. Apparatus as defined in claim 5 in which partition elements extend spanwise along the covering in series chordwise thereof and the joining positions of said elements with said walls of the covering are offset in a chordwise direction.

7. Apparatus as defined in claim 5 in which said partition elements are joined to said walls along lines parallel one to another and offset in a direction normal to said lines.

8. Apparatus as defined in claim 5 in which said partition elements extend spanwise along the covering in series chordwise thereof and are joined to said walls along spanwise lines parallel one to another and offset in a chordwise direction providing a plurality of inflatable passages in chordwise series extending spanwise of said covering, said passages being in communication one to another for simultaneous inflation of said covering.

9. Apparatus for preventing the accumulation of ice upon the leading edge of an airfoil, said apparatus comprising a covering of resilient rubber-like material for said leading edge having inner and outer walls in separated relation one to another, the outer wall having a plurality of panels of said material spaced apart spanwise and extending chordwise of the covering in parallel relation one to another, means for inflating said covering to distend said outer wall and effect separating movement thereof away from the inner wall, and a plurality of interposed partition elements at each of said panels disposed spaced-apart in chordwise series and extending spanwise of the covering providing inflatable passages in communication with one another, said elements connecting said walls at each of said panels and joined to said outer wall along spanwise lines parallel one to another and at positions offset chordwise with relation to their positions of joinder with said inner wall in a manner to effect swinging movement of said elements under the separating movement of said outer wall to compel shifting of said outer wall at said panels thereof relative to said inner wall in a chordwise direction of the covering, said elements being constructed and arranged at adjacent panels in a manner to compel the shifting of said outer wall at said adjacent panels in opposed chordwise directions.

10. Apparatus for preventing the accumulation of ice upon a surface, said apparatus comprising a covering having an inner wall, an outer wall of distensible material in separated relation with respect to said inner wall, means for distending said outer wall and effecting separating movement thereof relative to said inner wall, and a plurality of interposed restraining elements connecting said walls and joined to said outer wall at positions offset unidirectionally of the covering with relation to their positions of joinder with said inner wall in a manner to effect swinging movement of said elements under the separating movement of said outer wall and to facilitate localized distension of said outer wall at portions thereof intermediate the positions of joinder of said elements with said outer wall.

11. Apparatus for preventing the accumulation of ice upon a surface, said apparatus comprising a covering having an inner wall, an outer wall of elastic material in separated relation with respect to said inner wall, means for distending said outer wall and effecting separating movement thereof relative to said inner wall, and a plurality of interposed restraining elements of elastically stretchable material connecting said walls and joined to said outer wall at positions offset unidirectionally of the covering toward a margin of the covering with relation to their positions of joinder with said inner wall in a manner to effect swinging movement of said elements under the separating movement of said outer wall and to facilitate by virtue of the stretchability of said elements localized distension of said outer wall at portions thereof intermediate the positions of joinder of said elements with said outer wall.

12. Apparatus for preventing the accumulation of ice upon a surface, said apparatus comprising a covering having an inner wall, an outer wall of distensible material in separated relation with respect to said inner wall, and means for distending said outer wall and effecting separating movement thereof away from said inner wall, and a plurality of interposed partition elements of stretchable strip material including elastic material extending side-by-side in said covering in spaced-apart relation one to another and connecting said walls and joined to said outer wall at positions offset unidirectionally of the covering toward a margin of the covering with relation to their positions of joinder with said inner wall in a manner to effect swinging movement of said elements under the separating movement of said outer wall and to facilitate by virtue of the stretchability of said elements localized distension of said outer wall at portions thereof intermediate the positions of joinder of said elements with said outer wall.
